INDUCTION TRAIN-CONTROL SYSTEM

Application filed May 4, 1923. Serial No. 636,552.

This invention relates to automatic train control systems, and has special reference to the provision of an improved automatic train control system of the induction type.

5 A principal object of the present invention comprehends the provision of an induction train control system in which train carried mechanism is operated to produce a plurality of different effects responsive to the cooperation between vehicle carried and roadside inductor means, the construction and the cooperation being such that the vehicle carried inductor means is influenced by the roadside inductor means to produce a controlling, such as a tripping action of the vehicle carried mechanism, to control the movement of the vehicle, and is then influenced under one or more different roadside conditions to produce a modifying or resetting action of the vehicle 10 carried mechanism.

15 A further principal object of the present invention relates to the provision of an inductive system of the type referred to in which the vehicle carried and roadside inductor means are operated by means of a vehicle carried source of energy.

20 A still further principal object of the invention includes the provision of a system of the nature referred to in which the vehicle carried and roadside inductor means are constructed so as to cooperate for periodically producing a controlling or tripping operation of the train carried mechanism or for producing such an operation only under "danger" and "caution" roadside conditions, and for producing a resetting action of the vehicle carried mechanism under "caution" and "clear" roadside conditions when the same 25 has been tripped.

25 Further objects of the invention include the provision of an induction system in which a vehicle carried inductor is employed for energizing the vehicle carried mechanism, the said energizing inductor functioning also in cooperation with the roadside mechanism for producing the controlling or tripping operation of the vehicle carried mechanism, and for producing the resetting thereof; and the further provision of a system of this nature in which the parts of the system are coor-

dinated to produce "proceed", "proceed at caution" and "stop" effects in the vehicle in response to "clear", "caution" and "danger" conditions on the roadside.

30 To the accomplishment of the foregoing and such other objects as may hereinafter appear, our invention consists in the elements and their relation one to the other, as hereinafter particularly described and sought to be defined in the claims, reference being had to the accompanying drawings which show a preferred embodiment of our invention and in which:

35 Fig. 1 is a view showing a track subdivided into blocks or sections with the roadside inductor means in each section,

40 Fig. 2 is a view showing the vehicle carried mechanism and the cooperating roadside mechanism,

45 Fig. 3 is a view showing a modification of the roadside mechanism,

50 Fig. 4 is a detail view showing a modified form of vehicle carried inductor means, and

55 Figs. 5 and 6 are views showing two modifications of the inductive train control system of our invention.

60 Before describing in detail the system of our invention, we will briefly premise that in our inductive train control system a train control mechanism, such as a valve V which may control the train line of an air brake system, is operated by means of train carried energy such as the alternating current generator G, and is controlled by the cooperation of a vehicle carried inductor means generally designated as A and a roadside inductor means generally designated as B, the vehicle carried and roadside inductor means A—B 65

70 cooperating to periodically produce a controlling operation of the valve V or to produce such an operation under one or more roadside conditions such as a "danger" or "caution" condition and to modify such controlling operation of the valve V by a resetting action under "clear" and "caution" roadside conditions.

75 The valve V may be any suitable valve for controlling the flow of air in the train line of an air brake system, such valve being pref-

erably of the type shown in the patent to A. G. Shaver No. 1,411,526 of April 4, 1922. The valve V is controlled by means of an electromagnet 10 which is normally energized by a vehicle carried circuit designated for convenience as *h* (see Fig. 2) and comprising the generator G, conductors 11, 12 and 13, contact 14 which is normally closed by the energization of a relay F, conductor 15, conductor 16, coil of electromagnet 10 and conductors 17, 18 and 19.

In the preferred embodiment of our invention, the circuit *h* is controlled and operated to produce "proceed," "proceed at caution" and "stop" effects in response to "clear," "caution," and "danger" roadside conditions. Under "clear" roadside conditions the circuit *h* is closed at the contact 14 due to the energization of the relay F, which relay is deenergized under "danger" roadside conditions to effect the opening of the contact 14 and the opening and the deenergizing of the circuit *h* and electromagnet 10 respectively. Under "caution" track conditions the circuit

h is controlled by a branch or partial circuit arranged in parallel with the contact 14, the said branch or partial circuit comprising the conductor 20, a speed circuit controller 21, the contacts of which are closed when the vehicle is traveling at or below a predetermined speed and are opened when the vehicle exceeds such speed, conductor 22, contact 23 controlled by a relay H, and conductor 24. Under "caution" track conditions the relay H is energized to close the contact 23, placing the circuit *h* under the control of the speed circuit controller 21 so that when the speed of the vehicle under the "caution" track conditions does not exceed the predetermined or fixed speed, the electromagnet 10 is energized to permit the train to proceed under restriction; and when such speed of the vehicle is exceeded, the electromagnet 10 is energized to operate the train venting valve V to bring the train to a stop.

The relays F and H are operated by means of the vehicle carried source of energy G and are controlled by the cooperation of the vehicle carried and roadside inductor means A—B. The relay F is a two-element relay having the field *f* and the armature *f'* arranged in series in a stick circuit which may be designated for convenience as *i* comprising the contact 25 controlled by the relay F, the conductor 26, conductor 27, condenser 28, the coil of an inductor element *b*, conductor 29, the coil of an inductor element *c*, conductor 30, relay element *f'*, conductor 31, relay element *f* and conductor 32. This circuit *i* is normally energized by a circuit, which for convenience may be designated as *k*, comprising the generator G, conductor 11, conductor 34, the coil of an inductor element *a*, conductor 35 and conductors 18 and 19. The elements *a*, *b* and *c* are inductively related so that under nor-

mal conditions with the circuit *i* closed, the relay F is energized to maintain its contacts 14 and 25 closed.

The relay H is also a two-element relay having the field *h'* and the armature *h* arranged in series in a stick circuit which may be designated as *l* comprising a contact 36 which is open under normal conditions and which is closed when the relay H is energized in response to "caution" conditions, as will become clearer hereinafter, a conductor 37, the conductor 27, condenser 28, element *b*, conductor 29, inductor element *c*, conductor 30, a conductor 38, relay element *h*, conductor 42, relay element *h'*, and conductor 43. The inductors *b* and *c* being inductively related to the energizing inductor *a*, when the circuit *l* is closed, the relay H will be energized from the energizing circuit *k* and the generator G. Condenser 28 is provided in the circuits *i* and *l* respectively, for the purpose of adjusting these circuits to the proper state of impedance.

Cooperating with the inductor elements *a*, *b* and *c* of the vehicle carried inductor means A, there is provided a roadside magnetic element E forming part of the roadside inductor means B, the said element E, in the form of the invention illustrated in Figs. 1 and 2, comprising an inert element located at a controlling point or station and positioned preferably between the rails *r*, *r*, an inert element E being provided for each section or block of the track such as the sections X and Y shown in Fig. 1; and the cooperation between the vehicle carried inductor elements *a*, *b* and *c* and the inert track element E is such that in the movement of the vehicle and the vehicle carried mechanism in the direction as indicated by the arrow in Fig. 1, the vehicle inductor elements will move over so as to be influenced by the roadside element E to produce a controlling operation of that relay F or H which is in an energized state.

The operation of the system thus far described is as follows: When the train is running without restriction between control stations, the energizing vehicle inductor *a* functions in the nature of the primary of a transformer, the secondaries of which are the inductor elements *b* and *c* which are energized for operating the relay F in the circuit *i* to maintain the train control circuit *h* normally closed. When the train reaches a control station the vehicle carried inductor elements *a*, *b* and *c* move over and cover the roadside element E, and the vehicle carried inductor elements are influenced to produce a controlling such as a "tripping" operation in the relay F due to a diverting or shunting of the magnetic flux of the inductor *a* by the element E and due to a change in the reluctance of the magnetic circuits of the vehicle carried inductors *a*, *b* and *c* produced by the presence of the inert element E, the change in the reluctance

of the magnetic circuit of the elements *b* and *c* having the effect of changing the state of impedance of the train carried circuit *l*, resulting in an effective deenergization of the control relay *F*. Similarly when the train is running under "caution" conditions between control stations and the vehicle carried circuit *l* is closed for energizing the relay *H*, the vehicle carried inductor elements *a*, *b* and *c* again function in the nature of a transformer, the element *a* acting as the primary or energizing inductor, and the elements *b* and *c* as the secondary or receiving inductor for the circuit *l* for energizing the relay *H* and maintaining the circuit *l* closed. When, however, the train running under "caution" conditions reaches a control station, the vehicle inductor elements *a*, *b* and *c* move over and are influenced by the inert element *E* to divert or shunt the flux flowing thru the transformer secondary and to change the state of impedance of the train carried circuit *l* for producing an effective deenergization of the relay *H*, the deenergization of this relay causing the opening of the control circuit *h* at the contact 23 and causing the opening of the stick circuit *l* at the contact 36.

It will thus be seen that with the provision of the system described, a train running under "clear" or "caution" conditions will always be influenced when passing a control station for producing a tripping of the train relays to effect a "stop" indication in the train mechanism and that the "stop" indication will persist in the absence of any modifying influence or resetting operation.

For the purpose of preventing a "stop" indication produced by the tripping of either relay *F* or *H* from becoming effective to operate the brake valve magnet 10 under "clear" or "caution" roadside conditions, there is provided cooperating vehicle and roadside inductor means for modifying the controlling operation produced by the inert element *E*, the modifying comprehending the resetting of the relay *F* under "clear" track conditions to close the circuit *h* so as to permit the train to proceed without restriction, or the resetting of the relay *H* under "caution" track conditions to place the control circuit *h* under the control of the speed controller 21 to permit the train to proceed under a speed limitation.

For resetting the relay *F*, we preferably provide a reset partial circuit including the conductors 56 and 57 and contact 58, these parts being arranged in parallel with the stick contact 25 of the relay *F*, the contact 58 being controlled by an indication receiver *F'* which may be of the two-element type having a field f^2 always energized from the vehicle carried generator *G* and connected thereto by means of the conductors 59 and 60 connected to the conductors 19 and 11 respectively, and an armature f^3 included in a circuit which may be designated as *o* comprising the armature f^3 ,

conductor 61, coil of a vehicle carried inductor *d*, and conductor 62.

For resetting the relay *H* we preferably provide a resetting partial circuit comprising a conductor 63, conductor 64, contact 65, conductor 66 and conductor 67, this partial circuit being arranged in parallel with the stick contact 36 of the relay *H*, the contact 65, being controlled by an indication receiver *H'* which may also be of the two-element type having the field h^3 energized from the generator *G* and connected thereto by means of the conductors 68 and 69, and the armature h^4 arranged in a circuit which may be designated as *p* comprising the armature h^4 , conductor 70, coil of a vehicle carried inductor element *e*, and conductor 71.

Cooperating with the vehicle carried inductor elements *d* and *e* there are provided roadside inductor elements *d'* and *e'* which are selectively energized by means to be described presently for inductively influencing the vehicle carried inductor elements *d* and *e* in the movement of the vehicle over the roadway.

For inductively influencing the vehicle carried inductor element *d* the roadside element *d'* is arranged on the roadway so that the vehicle element *d* moves thereover when the vehicle passes a controlling station and is arranged in a roadside circuit *m* including a conductor 45, a roadside inductor element *a'* positioned so as to correspond and be in inductive relation with the vehicle carried energizing inductor *a*, conductor 46, a condenser 47, conductor 48, a contact 49 controlled by a home or track relay *T*, a conductor 50, a contact 51 controlled by a distant relay *D*, conductor 52 and coil of the inductor element *d'*, the condenser 47 being provided in this circuit for correcting the impedance factor thereof.

The home and distant relays *T* and *D* are operated in accordance with roadside conditions as will be described presently, so that under "clear" roadside conditions both of these relays are energized to close the contacts 49 and 51 for closing the roadside inductor circuit *m*. Under such "clear" roadside conditions with the circuit *m* closed, the vehicle carried energizing inductor *a* energizes the roadside inductor element *a'*, the said roadside element functioning as a receiving inductor for producing an impulse which is transmitted to the roadside transmitting inductor *d'*, an impulse being in turn transmitted by the element *d'*, to the receiving inductor element *d*, the received impulse being sufficient to energize the armature f^3 of the indication receiver *F'*. Thus under "clear" roadside conditions after the relay *F* has been tripped or deenergized by the inert element *E*, the indication receiver *F'* is energized by the cooperation of the train and track inductors to close the contact 58 controlled thereby for the energizing of the relay *F*, energization

of the relay effecting the closing of contacts 14 and 25 controlled thereby. It will be understood that the closing of the contact 25 closes the vehicle circuit *i* and permits the energization of the relay *F* from the energizing circuit *h* due to the resumed activity of the transformer combination *a*, *b* and *c* after the same has passed an inert element *E*. It will be further apparent that due to the closing of the stick contact 25 the energization of the circuit *i* will persist after the vehicle carried element *d* passes beyond the roadside element *d'*.

For inductively influencing the vehicle carried inductor *e* to operate the indication receiver *H'*, the roadside inductor element *e'* is arranged for inductive cooperation with the vehicle carried inductor *e* in the movement of the vehicle over the roadway, and is arranged in another circuit generally designated as *n* including the conductor 53, the coil of the element *e'*, conductor 54, back contact 55, contact 51 normally open and closed when the relay *D* is deenergized, conductor 50, contact 49, conductor 48, condenser 47, conductor 46, and receiving inductor element *a'*.

Under "caution" roadside conditions the distant relay *D* is deenergized as will appear hereinafter, and the contact 51 will drop onto its back contact 55 to close the inductor circuit *n*. When the vehicle carried inductor means *A* passes the inductor means *B* under such "caution" roadside conditions, after a tripping operation of the train mechanism has taken place, the roadside receiving inductor *a'* which receives energy from the vehicle energizing inductor *a* transmits such energy to the roadside transmitting inductor *e'* for producing an impulse in the corresponding vehicle carried inductor *e*, the said impulse being sufficient to energize the armature *h'* of the indication receiver *H'* to momentarily close the contact 65 of the reset circuit controlling the relay *H*. It will be understood that when the relay *H* is energized, the contacts 23 and 36 controlled thereby are closed, the closing of the contact 36 resulting in the energization of the relay *H* by the transformer combination *a*, *b* and *c*, the transformer combination having resumed activity after passing the inert element *E*. It will be further understood that since the stick contact 36 is now closed, the circuit *l* will persist in an energized state even after the vehicle inductor element *e* passes the roadside inductor element *e'*.

Under "danger" track conditions the home and distant relays *T* and *D* will both be deenergized as will appear hereinafter, and both the roadside inductor circuits *m* and *n* will be opened due to the opening of the contact 49 so that the tripping or deenergizing of either relay *F* or *H* by the roadside element *E* will not be modified when the vehicle inductor elements *d* and *e* move over the road-

side inductor elements *d'* and *e'* and the train will therefore be brought to a halt. To permit the train to proceed to the next control station, there is provided manually operated means for energizing the relay *H* to permit the train to proceed under restriction, such means comprising a manually reset partial circuit including the conductor 74, switch 75 and conductor 76, this partial circuit being in parallel with the contact 65. By closing the switch 75 it will be understood that the relay *H* will be energized for closing its contacts, and the control circuit *h* will thereby be placed under the control of the speed circuit controller 21.

The home and distant relays *T* and *D* associated with the inductor roadside means *B* of any given block are controlled respectively by the block in advance and the second block in advance, and to this end the home relays *T* may be connected to the insulated rail sections *r*, *r* of a block by means of the conductors 77 and 78, the relay *T* being energized by means of a track battery 79 provided for each block; and the distant relay *D* of each block is controlled by the home relay *T* of the next succeeding block, such control being provided for example by placing a distant relay *D* in a circuit controlled by the home relay *T* of the block in advance, the circuit including conductor 80, battery 81, conductor 82, contact 83 under the control of the track relay *T* of the next block in advance, conductor 84, and coil of the distant relay *D*.

The operation of the train control system shown in Figs. 1 and 2 is substantially as follows: When the train is running between control stations without restriction, the vehicle relay *F* is in an energized state and the vehicle relay *H* is in a deenergized state; and when the train is running between control stations under a speed restriction, the relay *H* is in an energized state and the relay *F* in a deenergized state. When such a vehicle running either with or without restriction passes a control station, the vehicle carried inductor means *A* cooperates with the element *E* of the roadside inductor means *B* to produce a tripping or a deenergizing of either the relay *F* or *H* according to which happens to be energized. If the control station indicates "clear" roadside conditions, the vehicle inductor elements *a*, *d* cooperate with the roadside inductor elements *a'*, *d'* to reset or re-energize the relay *F* so as to permit the train to proceed without restriction. If, however, the control station indicates "caution" conditions ahead, the vehicle inductor elements *a* and *e* cooperate with the roadside inductor elements *a'* and *e'* to operate or reset the vehicle carried relay *H* to place the train under speed restriction. If however the control station indicates "danger", the relays *F* and *H* will remain deenergized and the train will be brought to a halt, and may then be made to

proceed under restriction by operation of the switch 75.

Referring now to Fig. 3 of the drawings, we show a modification of the roadside inductor means which is here generally designated as B', this roadside inductor means comprising resetting elements and resetting inductor circuits similar to those heretofore described, the parts being here designated by similar reference characters, and a tripping mechanism E' which differs from the inert magnetic tripping element E shown in Fig. 2, the tripping element E' comprising three inductor coils 85, 86 and 87 arranged in a circuit generally designated as s including the three inductor coils in series, the conductor 88, condenser 89, conductor 90, contact 91 under the control of the distant relay D, conductor 92, contact 93 under the control of the home relay T, and conductor 94, the condenser 89 being provided in this circuit for adjusting the impedance of the same. With this arrangement under "clear" conditions ahead no tripping of the relay F will take place, the relays F and H being operated to tripped condition only when the contact 91 or 93 is opened in response to "caution" or "danger" roadside conditions.

Referring now to Fig. 4 of the drawings, we show a modification of the vehicle carried inductor combination a, b and c, the coil of the energizing inductor a being provided with one or more turns such as 96 and 97 wound about the cores of the inductor elements c and b respectively, the construction being such that these windings act as opposing or bucking windings, the current therein opposing the induced current in the elements b and c, the opposition being just sufficient to neutralize any such induced current which may result from magnetic leakage between the inductor elements when the same move over the tripping element E.

Referring now to Fig. 5 of the drawings, we show a modification of our inductive train control system embodying a three speed control of the vehicle carried mechanism, the said mechanism including a vehicle carried inductive means which is responsive to a change of current characteristic in the circuits thereof and a roadside inductive means operable for transmitting currents of different characteristics to the vehicle carried inductor means to operate the same.

The three speed control of the vehicle carried mechanism includes a high, medium and low speed control effective under "clear," "caution" and "danger" track conditions respectively. Under "clear" track conditions the brake valve V is maintained closed by the energization of an electromagnet 110 which is energized under "clear" running conditions of the vehicle by a circuit including the generator G, the conductor 111, electromagnet 110, conductor 112, conductor 113,

contact 114 normally closed, conductor 115 leading to the high speed contact point 116, speed circuit controller 121, conductor 117 and conductor 119. Under "clear" running conditions of the train this circuit is controlled at the high speed contact point 116, the operation being such that the train is permitted to proceed only when moving at or below a predetermined high speed. Under "caution" or "danger" track conditions the contact 114 will be opened as will become clearer hereinafter for effecting the opening of this circuit and the deenergization of the magnet 110 in the absence of any modifying influence.

Under "caution" roadside conditions the medium speed control of the electromagnet 110 is effective by means of a circuit including the generator G, conductor 111, electromagnet 110, conductor 112, conductor 118, a contact 120 which is open as shown and which is adapted to be closed manually as will appear presently, conductor 121, conductor 122, conductor 124, contact 123, which is closed under "caution" track conditions as will appear hereinafter, conductor 126 leading to the medium speed control contact 127 closed by the speed circuit controller 121 when the vehicle reaches a predetermined medium speed and conductors 117 and 119. This circuit is normally open at the contacts 120 and 123, and in rendering the circuit operative the contact 123 is closed automatically as will be seen hereinafter, and the contact 120 if open must be closed manually by operation of the push key mechanism 128. Upon operation of the push key 128 the contact 120 will be closed and if the speed of the vehicle has reached the predetermined medium speed the contact 120 will be held in closed position by the energization of an electromagnet 129 energized by a circuit comprising the conductor 111, the conductor 130, electromagnet 129, a conductor 131, contact 132, conductor 122, conductor 124, contact 123, conductor 126 medium speed contact point 127, speed circuit controller 121, and conductors 117 and 119. By this means the medium speed circuit controlling the valve V cannot become effective until the speed of the vehicle is at or below the predetermined medium speed and "caution" conditions exist on the roadside.

Under "danger" roadside conditions the valve V is controlled to permit the train to proceed at a predetermined low speed by means of a circuit comprising generator G, the conductor 111, electromagnet 110, conductor 112, conductor 118, contact 120, conductors 121 and 122, a low speed contact 133, speed circuit controller 121 and conductors 117 and 119. This circuit, it will be noted, is normally open at the contact 120 and is not controlled by either of the automatically operated contacts 123 and 134, the said cir-

cuit being manually controlled by operation of the key 128 and controlled so that the train may be permitted to proceed at or below the predetermined low speed only after the speed of the train has been reduced to such predetermined speed. To prevent the low speed control from becoming otherwise effective, the key 128 is of the single impulse type disclosed in the copending application of A. G. Shaver Serial No. 634,053, filed April 23, 1923, and is so operative as to prevent the contact 120 from holding its closed position unless the electromagnet 129 is energized. For the low speed the electromagnet 129 is energized only when the train reaches the predetermined low speed, the energization resulting from the closing of the following circuit: generator G, conductor 111, conductors 130 and 131, contact 132 closed when the key 128 is operated, conductor 122, low speed contact point 133, speed circuit controller 121, and conductors 117 and 119. This circuit it will be seen may be closed only when the train reaches the low speed and the electromagnet 129 will remain energized for permitting low speed control only when the train maintains a speed at or below the predetermined minimum.

For controlling the valve V under "clear" and "caution" conditions, the contacts 114 and 123 are operated by means of a relay mechanism F^2 and controlled by the cooperation of the vehicle carried inductor means A^2 and the roadside inductor means B^2 . The relay mechanism F^2 is of a type which is responsive to a change in the current characteristic in either the field or armature and comprises the field f^4 common to two armatures f^5 and f^6 , the said armatures being operative for controlling the contacts 123 and 114 and additional contacts 136 and 125 and operating these contacts so that when the current in the armatures f^5 and f^6 is in phase with that in the field f^4 , the contacts 125 and 114 will be moved to closed position and the contacts 136 and 123 will be moved to open position, and when the current in the said armatures is 180° out of phase with that in the field f^4 , the contacts 136 and 123 will be operated to closed position and the contacts 125 and 114 will be operated to open position. By this means it will be noted that the contacts are positively operated electrically to both the operative and inoperative positions.

The field f^4 is normally energized from an inductor a^2 by means of the circuit comprising the field f^4 , condenser 134, conductor 135, a resistance 137, resistance 138, conductor 139, coil of the inductor element a^2 , and conductor 140. The inductor element a^2 is related inductively to the two inductor elements b^2 and c^2 , the latter inductors being arranged in an energizing circuit including the generator G, the conductor 141, winding

of element b^2 , a bucking winding 142, winding of element c^2 , and conductor 143. With this arrangement it will be understood that normally, as when the train is running under "clear" conditions between control stations, the field f^4 will be energized due to the inductive coupling between the elements a^2 , b^2 and c^2 .

The armatures f^5 and f^6 of the relay F^2 are arranged in series and are controlled by the following circuits: Under "clear" running conditions the energizing circuit for the armatures includes the resistance 138 which presents an energizing potential drop, the conductor 144, the armatures f^6 and f^5 in series, conductor 145, contact 125 closed, and conductor 146. Under "caution" running conditions the energizing circuit for the armatures comprises the resistance 137 which presents an energizing potential drop, conductor 144, armatures f^6 and f^5 in series, conductor 145, contact 136 closed under "caution" conditions, conductor 147, and conductor 148. With this arrangement it will be seen that the resistances 138 and 137 energize the armatures with currents of different phases, the arrangement being such that the resistance 138 energizes the armatures with a current in phase with that in the field f^4 , and the resistance 137 energizes the armatures with current 180° out of phase with that in the field f^4 .

For producing a controlling condition in the relay mechanism the roadside mechanism B^2 includes the tripping element E^2 which may be controlled in a manner such as that heretofore described in connection with Fig. 3, the tripping element E^2 being controlled by a roadside circuit closed under "clear" track conditions and opened under "caution" and "danger" track conditions, the said circuit comprising the coil of the element E^2 , condenser 150, conductor 151, contact 152 under the control of distant relay D^2 , conductor 153, contact 154 under the control of a home relay T^2 , and conductor 155. It will be understood that under "caution" or "danger" track conditions with this circuit open the vehicle inductors a^2 , b^2 and c^2 are influenced to effect the effective deenergization of the relay mechanism F^2 .

For modifying the control of the relay mechanism under "caution" and "danger" track conditions, cooperative vehicle and roadside resetting means are employed operating as heretofore mentioned by change in the current characteristic in the roadside and vehicle inductor means. The vehicle resetting means comprises an indication receiver H^2 having a field h^5 always energized from the generator G and connected to the conductors 111 and 119 by means of the conductors 156 and 157, and the armatures h^6 and h^7 arranged in series in a circuit including the conductor 158, the inductor element

d^2 , conductor 159, inductor element e^2 , and conductor 160. The field and armatures of the indication received H^2 are so inter-related that when a current in phase with the current in the field h^5 is passed through the armatures h^6 and h^7 , the armatures will be moved or operated to close a contact 161 and to open a contact 162, and when the current in the armatures h^6 and h^7 is of a phase opposite to that in the field h^5 , the contact 161 will be moved to an open position and the contact 162 will be moved to a closed position.

The contact 161 controls a reset partial circuit which is in parallel with the contact 125, the said partial circuit including the conductor 163, contact 161, and conductor 164. When the contact 161 is closed, it will be seen that the armatures f^5 and f^6 will be energized with an "in phase" current as explained with reference to the normal circuit for f^5 and f^6 under "clear" conditions. Contact 162 controls a partial circuit for resetting the armature f^5 , the said partial circuit including the conductor 164, contact 162, and conductor 165, this partial circuit being therefore in parallel with the stick contact 136. When the contact 162 is closed, it will be understood that the armatures f^5 and f^6 are energized with an "out of phase" current as already explained with reference to the normal circuit for f^5 and f^6 under "caution" conditions.

For selectively producing the "in phase" and "out of phase" currents in the armatures h^6 and h^7 of the indication receiver H^2 , the roadside inductor means B^2 includes resetting inductor elements inter-related to transmit impulses of different characteristics to the vehicle carried inductors. The roadside resetting elements include an inductor a^2 arranged to receive energy from the energizing inductors b^2 and c^2 , and transmitting inductor elements d^2 and e^2 , arranged to cooperate respectively with the vehicle inductor elements d^2 and e^2 to transmit to the latter impulses received from the inductor element a^2 .

The roadside inductor elements a^2 , d^2 and e^2 are so inter-related that under "clear" roadside conditions the inductor element a^2 will energize the inductor elements e^2 and d^2 with a current of one phase, and under "caution" track conditions will energize the said inductor elements with a current of an opposite phase. To produce this operation the roadside inductor elements are inter-connected by circuits controlled by a distant relay D^2 and a home relay T^2 , the circuits including the condenser 167, conductor 168, front and back contact points 169 and 170, the front contact point being closed by the contact 171 when the relay D^2 is energized, conductor 172, contact 173, conductor 174, inductor element e^2 conductor 175, inductor ele-

ment d^2 , conductor 176, contact 177, conductor 178, contact 179, front contact point 180, conductor 181, and inductor element a^2 , this circuit being operative under "clear" track conditions. Under "caution" track conditions the distant relay D^2 is deenergized and the contact 179 makes with the back contact point 170, the contact 171 making with a back contact point 182 connected to the conductor 181, the circuit connections between the inductor element a^2 and the inductor elements d^2 and e^2 being thereby reversed for producing in the inductor elements d^2 and e^2 an impulse of a phase opposite to that produced under "clear" track conditions. Under "danger" track conditions the home and distant magnets T^2 and D^2 will both be deenergized, opening the contacts 177 and 173 with the result that no impulse is transmitted to the inductor elements e^2 and d^2 when the vehicle carried inductor means moves over the roadside inductor means.

Referring now to Fig. 6 of the drawings, we show a still further modification of our invention, the system shown in Fig. 6 being similar to that shown in Fig. 5 with the exceptions that a three-position relay mechanism and a three-position indication receiver means is provided in lieu of that shown in Fig. 5, the roadside mechanism including an inert magnetic element operating in a manner similar to the system shown in Fig. 2. The other parts of the system are similar to that shown in Fig. 5 and are designated by similar reference characters.

In the system shown in Fig. 6 we employ a three-position relay mechanism designated as F^2 including a field f^8 and a single armature f^9 , the said armature being operative to actuate the contacts 114 and 125 to closed position when the current in the armature f^9 is in phase with that in the field f^8 , and to operate the contacts 123 and 136 to closed position when the current in the armature f^9 is 180° out of phase with that in the field f^8 . The indication receiver H^2 also comprises a three-position indicating means including a field h^8 and an armature h^9 operative to actuate the contacts 161 and 162 in a manner similar to that heretofore described in connection with the indication receiver H^2 . As mentioned the track element of the roadside inductor means comprises an inert element which is here designated as E^2 .

The operation of the systems shown in Figs. 5 and 6 will in the main be fully apparent from the above detailed description thereof, the operation of the system being generally similar to that described in detail in connection with Fig. 2, with the general exception that impulses or currents of different phases are selectively transmitted to the vehicle carried inductors both for controlling the operation of the relay mechanism and for operating the resetting means.

While we have shown our device in the preferred forms, it will be obvious that many changes and modifications may be made in the structure disclosed without departing from the spirit of the invention, defined in the following claims.

We claim:

1. In combination, vehicle carried mechanism, means for controlling the operation of the same including a vehicle carried energizing inductor and roadside mechanism for influencing the inductor to produce a controlling operation of said vehicle carried mechanism in the movement of the vehicle over a roadway, and means for determining the further operation of the vehicle carried mechanism including cooperating vehicle and roadside inductors associated with so as to be energized by said vehicle energizing inductor.

2. In combination, vehicle carried mechanism, means for controlling the operation of the same including a vehicle carried energizing inductor, a vehicle carried source of energy therefor and roadside mechanism for influencing the inductor to produce a controlling operation of said vehicle carried mechanism in the movement of the vehicle over a roadway, and means for determining the further operation of the vehicle carried mechanism including cooperating vehicle and roadside inductors associated with so as to be energized by said vehicle energizing inductor.

3. In combination, vehicle carried mechanism, means for controlling the operation of the same including a vehicle carried energizing inductor and roadside mechanism for influencing the inductor to produce a controlling operation of said vehicle carried mechanism in the movement of the vehicle over a roadway, and means for determining the further operation of the vehicle carried mechanism including vehicle impulse receiving and roadside impulse transmitting inductoriums and a roadside impulse receiving inductor arranged to receive energy from said energizing inductor and to transmit the same to the inductoriums.

4. In combination, vehicle carried mechanism, means for controlling the operation of the same including a vehicle carried energizing inductor and roadside mechanism for periodically influencing the inductor to produce a controlling operation of said vehicle carried mechanism in the movement of the vehicle over a roadway, and means for periodically determining the further state of operation of the vehicle carried mechanism including cooperating vehicle and roadside inductors associated with so as to be energized by said vehicle energizing inductor.

5. In combination, vehicle carried mechanism, means for controlling the operation of the same including a vehicle carried energizing inductor and roadside mechanism for influencing the inductor to produce a controlling operation of said vehicle carried mechanism including cooperating vehicle and roadside inductors associated with so as to be energized by said vehicle energizing inductor.

6. In combination, vehicle carried mechanism including a normally closed operating circuit, means for holding the circuit closed including a vehicle carried energizing inductor, means effective for opening the circuit including roadside mechanism for influencing the inductor in the movement of the vehicle over a roadway, and means for determining the further operation of the said circuit including cooperating vehicle and roadside inductors associated with so as to be energized by said vehicle energizing inductor.

7. In combination, vehicle carried mechanism including a normally closed operating circuit, means for holding the circuit closed including a vehicle carried energizing inductor, means effective for opening the circuit including roadside mechanism for influencing the inductor in the movement of the vehicle over a roadway, and means for determining the further operation of the said circuit substantially when the opening means is effective including cooperating vehicle and roadside inductors associated with so as to be energized by said vehicle energizing inductor.

8. In combination, vehicle carried mechanism, means including a vehicle carried energizing inductor and roadside mechanism for influencing the inductor to produce a predetermined effect in said vehicle carried mechanism in the movement of the vehicle over a roadway, and means for modifying the effect under given track conditions including cooperating vehicle and roadside inductors associated with so as to be energized by said vehicle energizing inductor.

9. In combination, vehicle carried mechanism, means including a vehicle carried energizing inductor and roadside mechanism for influencing the inductor to produce a "danger" effect in said vehicle carried mechanism in the movement of the vehicle over a roadway, and means for modifying the effect under "safe" track conditions to produce a "proceed" effect in said vehicle carried mechanism, said modifying means including cooperating vehicle and roadside inductors associated with so as to be energized by said vehicle energizing inductor.

10. In combination, vehicle carried mechanism, means for controlling the operation of the same including a vehicle carried energizing inductor and roadside mechanism for influencing the inductor to produce a controlling operation of said vehicle carried mecha-

nism in the movement of the vehicle over a roadway, and means for determining the further operation of the vehicle carried mechanism including a vehicle carried receiving inductor, a roadside transmitting inductor, a roadside receiving inductor arranged to be energized by the vehicle energizing inductor and roadside means operable in response to roadside conditions to connect and disconnect the roadside inductors.

10. 11. In an inductive train control system, vehicle carried train control mechanism, means for producing a controlling operation in the same comprising a vehicle carried transformer including primary and secondary coils and a roadside mechanism for shunting the secondary coil when the transformer is moved thereover, and means for determining the further operation of the train control mechanism including cooperating vehicle and roadside inductors associated with so as to be energized by said primary transformer coil.

12. In an inductive train control system, vehicle carried train control mechanism, means for producing a controlling operation in the same comprising a vehicle carried transformer including primary and secondary coils, a vehicle carried source of energy therefor and a roadside mechanism for shunting the secondary coil when the transformer is moved thereover, and means for determining the further operation of the train control mechanism including cooperating vehicle and roadside inductors associated with so as to be energized by said primary transformer coil.

13. In an inductive train control system, vehicle carried train control mechanism, means for producing a controlling operation in the same comprising a vehicle carried transformer having primary and secondary coils and a roadside mechanism for shunting the secondary coil when the transformer is moved thereover, and means for determining the further operation of the train control mechanism including vehicle impulse receiving and roadside impulse transmitting inductoriums, and a roadside impulse receiving inductor arranged to receive energy from said primary transformer coil and to transmit such energy to the inductoriums.

14. In an inductive train control system, vehicle carried train control mechanism including a normally closed operating circuit, means for holding the circuit closed including a vehicle carried transformer having primary and secondary coils, means effective for opening the circuit including roadside mechanism for shunting the secondary coil when the transformer is moved thereover, and means for determining the further operation of the said circuit including cooperating vehicle and roadside inductors associated with so as to be energized by said primary transformer coil.

15. In an inductive train control system, vehicle carried train control mechanism, means including vehicle carried primary and secondary transformer coils and roadside mechanism for influencing the same to produce a predetermined effect in said vehicle carried mechanism in the movement of the vehicle over a road way, and means for modifying the effect under given track conditions, the said last mentioned means including co-
70
75
operating vehicle and roadside inductors associated with so as to be energized by said primary coil.

16. In an inductive train control system, vehicle carried train control mechanism, means for controlling the operation of the same including a vehicle carried transformer having primary and secondary coils and roadside mechanism for influencing the said coils to produce a controlling operation of said vehicle carried mechanism in the movement of the vehicle over a roadway, and means for determining the further operation of the vehicle carried mechanism including a vehicle carried receiving inductor, a roadside transmitting inductor, a roadside receiving inductor arranged to be energized by the primary coil of said transformer, and roadside means operable in response to roadside conditions to connect and disconnect the roadside inductors.

17. In an inductive train control system, vehicle carried mechanism, means for producing a controlling operation in said mechanism comprising a vehicle carried control relay, a vehicle carried transformer having an energizing primary coil and a secondary coil, a vehicle carried circuit for the said relay and the secondary coil and a roadside mechanism for influencing the said transformer in the movement of the vehicle over a roadway; and means for determining the further operation of train carried mechanism comprising a vehicle carried indication receiver and cooperating vehicle and roadside inductors associated with so as to be energized by the primary coil of the transformer in the movement of the vehicle for operating the said indication receiver.

18. In an inductive train control system, vehicle carried mechanism, means for producing a controlling operation in said mechanism comprising a vehicle carried control relay, a vehicle carried transformer having an energizing primary coil and a secondary coil, a vehicle carried circuit for the said relay and the secondary coil and a roadside mechanism for influencing the said transformer in the movement of the vehicle to produce a controlling condition in said relay; and means for determining the further operation of said train carried mechanism comprising a reset circuit for said relay, an indication receiver for operating said reset circuit and cooperating vehicle and roadside inductors associated
115

with so as to be energized by the primary coil of the transformer in the movement of the vehicle for operating the indication receiver.

19. In an inductive train control system, vehicle carried mechanism, means for producing a controlling operation in said mechanism comprising a vehicle carried control stick relay, a vehicle carried transformer having an energizing primary coil and a secondary coil, a vehicle carried normally closed circuit for the said relay and the secondary coil and a roadside mechanism for influencing the said transformer in the movement of the vehicle to trip said relay and open said circuit; and means for determining the further operation of said train carried mechanism comprising a reset circuit for said relay, an indication receiver for operating said reset circuit and cooperating vehicle and roadside inductors associated with so as to be energized by the primary coil of the transformer in the movement of the vehicle for operating the indication receiver.

20. In an inductive train control system, vehicle carried mechanism, means for producing a controlling operation in said mechanism comprising a vehicle carried control stick relay, a vehicle carried transformer having an energizing primary coil and a secondary coil, a vehicle carried normally closed circuit for the said relay and the secondary coil and a roadside mechanism for influencing the said transformer in the movement of the vehicle to trip said relay and open said circuit; and means for determining the further operation of said train carried mechanism comprising a reset circuit for said relay, an indication receiver for operating said reset circuit, vehicle impulse receiving and roadside impulse transmitting inductoriums for operating the indication receiver and a roadside impulse receiving inductor arranged to receive energy from said primary transformer coil and to transmit the same to said inductoriums.

21. In an inductive train control system, vehicle carried mechanism, means for producing a controlling operation in said mechanism comprising a vehicle carried control relay, a vehicle carried transformer having an energizing primary coil and a secondary coil, a vehicle carried circuit for the said relay and the secondary coil and a roadside mechanism for periodically influencing the said transformer in the movement of the vehicle to produce a controlling condition in said relay; and means for periodically determining the further operation of said train carried mechanism comprising a reset circuit for said relay, an indication receiver for operating said reset circuit and cooperating vehicle and roadside inductors associated with so as to be energized by the primary coil of the transformer in the movement of the vehicle for operating the indication receiver.

22. In an inductive train control system, vehicle carried mechanism, means for producing a controlling operation in said mechanism comprising a vehicle carried control relay, a vehicle carried transformer having an energizing primary coil and a secondary coil, a vehicle carried circuit for the said relay and the secondary coil and a roadside mechanism for influencing the said transformer in the movement of the vehicle to trip said relay; and means for determining the further operation of said train carried mechanism comprising a reset circuit for said relay, an indication receiver for operating said reset circuit, cooperating vehicle and roadside inductors associated with so as to be energized by the primary coil of the transformer in the movement of the vehicle for operating the indication receiver, and roadside means operable in response to roadside conditions for controlling the energization of said inductors.

23. In an inductive train control system, vehicle carried mechanism, means for producing a controlling operation in said mechanism comprising a vehicle carried control relay, vehicle carried inductively coupled coils, a vehicle carried circuit for said relay and one of said coils and a roadside mechanism for influencing the said coils in the movement of the vehicle over a roadway; and means for determining the further operation of the train carried mechanism comprising a reset circuit for said relay, a vehicle carried indication receiver for operating the reset circuit, cooperating vehicle and roadside inductors for operating the said indication receiver, and a vehicle carried source of energy for energizing the vehicle inductor by way of the roadside inductor.

24. In an inductive train control system, vehicle carried mechanism, means for producing a controlling operation in said mechanism comprising a vehicle carried control relay, vehicle carried inductively coupled coils, a vehicle carried circuit for said relay and one of said coils and a roadside mechanism for influencing the said coils in the movement of the vehicle over a roadway; and means for determining the further operation of the train carried mechanism comprising a reset circuit for said relay, a vehicle carried indication receiver for operating the reset circuit, and cooperating vehicle and roadside inductors for operating the said indication receiver.

25. In an inductive train control system, vehicle carried mechanism, means for producing a controlling operation in said mechanism comprising a vehicle carried control relay, a transformer having primary and secondary coils, a vehicle carried stick circuit for said relay and said secondary coil and a roadside mechanism for influencing the said transformer in the movement of the ve-

hicle to trip the said relay; and means for determining the further operation of the train carried mechanism comprising a reset circuit for said relay, an indication receiver for operating said reset circuit, cooperating vehicle and roadside inductors for operating the said indication receiver, and a vehicle source of energy for energizing the vehicle inductor by way of the roadside inductor.

26. In an inductive train control system, vehicle carried mechanism, means for producing a controlling operation in said mechanism comprising a vehicle carried control relay, a transformer having primary and secondary coils, a vehicle carried stick circuit for said relay and said secondary coil and a roadside mechanism for influencing the said transformer in the movement of the vehicle to trip the said relay; and means for determining the further operation of the train carried mechanism comprising a reset circuit for said relay, an indication receiver for operating said reset circuit and cooperating vehicle and roadside inductors for operating the said indication receiver.

27. In combination, vehicle carried mechanism, means for controlling the operation of the same including a vehicle carried inductor and roadside mechanism for influencing the inductor to produce a controlling operation of said vehicle carried mechanism in the movement of the vehicle over a roadway; and means for determining the further operation of the vehicle carried mechanism including cooperating vehicle and roadside inductors associated with so as to be energized by said first mentioned vehicle carried inductor.

28. In combination, vehicle carried mechanism, means for controlling the operation of the same including a vehicle carried inductor, a circuit therefor including a vehicle carried source of energy and roadside mechanism for influencing the inductor to produce a controlling operation of said vehicle carried mechanism; and means for determining the further operation of the vehicle carried mechanism including vehicle impulse receiving and roadside impulse transmitting inductoriums and a roadside impulse receiving inductor arranged to receive energy from said vehicle carried inductor and to transmit the same to the inductoriums.

29. In an intermittent inductive train control system, vehicle carried mechanism, means including a vehicle carried inductor, a circuit therefor including a vehicle carried source of energy, roadside mechanism for influencing the inductor to produce a predetermined effect in said vehicle carried mechanism, and means for modifying the effect under given track conditions including cooperating vehicle and roadside inductors associated with so as to be energized by said first mentioned vehicle carried inductor.

30. In an inductive train control system, vehicle carried mechanism, means for producing a controlling operation in said mechanism comprising a vehicle carried control relay, means including a vehicle carried inductor and a roadside mechanism for influencing the said inductor in the movement of the vehicle over a roadway; and means for determining the further operation of the train carried mechanism comprising a vehicle carried indication receiver and cooperating vehicle and roadside inductors associated with so as to be energized by said vehicle carried inductor in the movement of the vehicle for operating the said indication receiver.

31. In an inductive train control system, vehicle carried mechanism, means for producing a controlling operation in said mechanism comprising a vehicle carried control relay, means including a vehicle carried inductor, a vehicle carried source of energy for energizing said inductor and a roadside mechanism for influencing the said inductor in the movement of the vehicle to produce a controlling operation in said relay; and means for determining the further operation of the train carried mechanism comprising a reset circuit for said relay, an indication receiver for operating said reset circuit and cooperating vehicle and roadside inductors associated with so as to be energized by the first mentioned vehicle carried inductor for operating the indication receiver.

32. In an inductive train control system, vehicle carried mechanism, means for producing a controlling operation in said mechanism comprising a vehicle carried control stick relay, means including a vehicle carried inductor, a vehicle carried source of energy for energizing said inductor and a roadside mechanism for influencing the said inductor in the movement of the vehicle to trip said relay; and means for determining the further operation of the train carried mechanism comprising a reset circuit for said relay, an indication receiver for operating said reset circuit and cooperating vehicle and roadside inductors associated with so as to be energized by the first mentioned vehicle carried inductor for operating the indication receiver.

33. In an inductive train control system, vehicle carried mechanism, means for producing a controlling operation in said mechanism comprising a vehicle carried control relay, means including a vehicle carried inductor, a vehicle carried source of energy for energizing said inductor and a roadside mechanism for influencing the said inductor in the movement of the vehicle to trip said relay; and means for determining the further operation of the train carried mechanism comprising a reset circuit for said relay, an indication receiver for operating said reset circuit, cooperating vehicle and roadside inductors associated with so as to be energized by

- the first mentioned vehicle carried inductor for operating the indication receiver and roadside means operable in response to roadside conditions for controlling the energization of said inductors.
34. In combination, vehicle carried mechanism selectively operable for producing different train control effects, means for controlling the operation of the same including a vehicle carried inductor and roadside mechanism for influencing the inductor to produce a controlling operation in said vehicle carried mechanism in the movement of the vehicle over a roadway, and means for selectively determining the further operation of the vehicle carried mechanism including a plurality of vehicle carried inductors and a plurality of roadside inductors cooperating therewith and associated with so as to be energized by said first mentioned vehicle carried inductor.
35. In combination, vehicle carried mechanism selectively operable for producing different train control effects, means for controlling the operation of the same including a vehicle carried energizing inductor and roadside mechanism for influencing the energizing inductor to produce a controlling operation of said vehicle carried mechanism in the movement of the vehicle over a roadway, and means for selectively determining the further operation of the vehicle carried mechanism including a plurality of vehicle carried inductors and a plurality of roadside inductors cooperating therewith and associated with so as to be energized by said vehicle carried energizing inductor.
36. In combination, vehicle carried mechanism selectively operable for producing different train control effects, means for controlling the operation of the same including a vehicle carried energizing inductor and roadside mechanism for influencing the inductor to produce a controlling operation of said vehicle carried mechanism in the movement of the vehicle over a roadway, and means for selectively determining the further operation of the vehicle carried mechanism including a plurality of vehicle carried impulse receiving inductors, a plurality of roadside impulse transmitting inductors cooperating therewith and a roadside receiving inductor arranged to be energized by said energizing vehicle carried inductor and to selectively transmit energy to the other inductors.
37. In combination, vehicle carried mechanism selectively operable for producing different train control effects, means for controlling the operation of the same including a vehicle carried inductor and roadside mechanism for periodically influencing the inductor to produce a controlling operation of said vehicle carried mechanism in the movement of the vehicle over a roadway, and means for periodically selectively determining the further operation of the vehicle carried mechanism including a plurality of vehicle carried inductors and a plurality of roadside inductors cooperating therewith and associated with so as to be energized by said first mentioned vehicle carried inductor.
38. In combination, vehicle carried mechanism selectively operable for producing different train control effects, means for controlling the operation of the same including a vehicle carried inductor, a vehicle carried source of energy for energizing the same and roadside mechanism for influencing the inductor to produce a controlling operation of said vehicle carried mechanism in the movement of the vehicle over a roadway, and means for selectively determining the further operation of the vehicle carried mechanism substantially when the controlling operation therein is produced including a plurality of vehicle carried inductors and a plurality of roadside inductors cooperating therewith and associated with so as to be energized by said first mentioned vehicle carried inductor.
39. In combination, vehicle carried mechanism selectively operable for producing different train control effects, means for controlling the operation of the same including a vehicle carried inductor and roadside mechanism for influencing the inductor to produce a controlling operation of said vehicle carried mechanism in the movement of the vehicle over a roadway, and means for selectively determining the further operation of the vehicle carried mechanism including a plurality of vehicle carried inductors, a plurality of roadside inductors cooperating therewith and associated with so as to be energized by said first mentioned vehicle carried inductor, and means selectively operable in response to roadside conditions for controlling the energization of the roadside inductors.
40. In combination, vehicle carried mechanism selectively operable for producing different train control effects in accordance with different track conditions, means for controlling the operation of the vehicle carried mechanism including a vehicle carried inductor, a vehicle carried source of energy therefor and roadside mechanism for influencing the inductor to produce a controlling operation of said vehicle carried mechanism in the movement of the vehicle over a roadway, and means operable in response to roadside conditions for selectively determining the operation of the vehicle carried mechanism including a plurality of vehicle carried impulse receiving inductors, a plurality of roadside impulse transmitting inductors cooperating therewith, a roadside impulse receiving inductor associated with so as to be energized by said first mentioned vehicle carried inductor.

ried inductor and changeable circuit connections between the roadside inductors.

41. In combination, vehicle carried mechanism selectively operable for producing different train control effects, means for controlling the operation of the same including a vehicle carried inductor, a vehicle carried source of energy therefor and roadside mechanism for influencing the inductor to produce a controlling operation of said vehicle carried mechanism in the movement of the vehicle over a roadway, and means for selectively determining the further operation of the vehicle carried mechanism including a plurality of vehicle carried impulse receiving inductors, a plurality of roadside impulse transmitting inductors cooperating therewith, a roadside impulse receiving inductor associated with so as to be energized by said first mentioned vehicle carried inductor, a circuit connecting said roadside inductors and pole changing and make and break means in said circuit.

42. In combination, vehicle carried mechanism selectively operable for producing different train control effects, means for controlling the operation of the same including a vehicle carried transformer having primary and secondary coils and roadside mechanism for shunting the secondary coil when the transformer is moved thereover, and means for selectively determining the further operation of the vehicle carried mechanism including a plurality of vehicle carried inductors and a plurality of roadside inductors cooperating therewith and associated with so as to be energized by said primary transformer coil.

43. In combination, vehicle carried mechanism selectively operable for producing different train control effects, means for controlling the operation of the same including a vehicle carried three element transformer having primary and secondary coils and roadside mechanism for shunting the secondary when the transformer is moved thereover, and means for selectively determining the further operation of the vehicle carried mechanism including a plurality of vehicle carried inductors and a plurality of roadside inductors cooperating therewith and associated with so as to be energized by the primary of the transformer.

44. In combination, vehicle carried mechanism selectively operable for producing different train control effects, means for controlling the operation of the same including a vehicle carried transformer having primary and secondary coils and roadside mechanism for shunting the secondary coil when the transformer is moved thereover, and means for selectively determining the further operation of the vehicle carried mechanism including a plurality of vehicle carried impulse receiving inductors, a plurality of roadside im-

pulse transmitting inductors cooperating therewith and a roadside impulse receiving inductor associated with so as to be energized by said primary transformer coil.

45. In combination, vehicle carried mechanism selectively operable for producing different train control effects, means for controlling the operation of the same including a vehicle carried transformer having primary and secondary coils and roadside mechanism for shunting the secondary coil when the transformer is moved thereover, and means for selectively determining the further operation of the vehicle carried mechanism including a plurality of vehicle carried inductors, a plurality of roadside inductors cooperating therewith and associated with so as to be energized by said primary transformer coil and means selectively operable in response to roadside conditions for controlling the energization of the roadside inductors.

46. In combination, vehicle carried mechanism selectively operable for producing different train control effects, means for controlling the operation of the same including a vehicle carried transformer having primary and secondary coils and roadside mechanism for shunting the secondary coil when the transformer is moved thereover, and means for selectively determining the further operation of the vehicle carried mechanism including a plurality of vehicle carried impulse receiving inductors, a plurality of roadside impulse transmitting inductors cooperating therewith, a roadside impulse receiving inductor associated with so as to be energized by said primary transformer coil and changeable circuit connections between the roadside inductors.

47. In an inductive train control system, vehicle carried mechanism selectively operable for producing different train control effects comprising a vehicle carried control relay mechanism, a vehicle carried inductor associated with said relay mechanism and a roadside mechanism for influencing the said inductor in the movement of the vehicle to produce a controlling operation in said relay mechanism; and means for selectively determining the further operation of the relay mechanism comprising reset circuits for said relay mechanism, an indication receiver means selectively operable for operating said reset circuits, a plurality of vehicle carried inductors for said indication receiver means and a plurality of roadside inductors cooperating therewith and associated with so as to be energized by said first mentioned vehicle carried inductor.

48. In an inductive train control system, vehicle carried mechanism selectively operable for producing different train control effects comprising a vehicle carried control relay mechanism, a vehicle carried transformer having primary and secondary coils associated with said relay mechanism and a road-

- side mechanism for influencing the said transformer coils in the movement of the vehicle to produce a controlling operation in said relay mechanism; and means for selectively determining the further operation of the relay mechanism comprising reset circuits for said relay mechanism, an indication receiver means selectively operable for operating said reset circuits, a plurality of vehicle carried inductors for said indication receiver means and a plurality of roadside inductors cooperating therewith and associated with so as to be energized by said primary transformer coil.
49. In an inductive train control system, vehicle carried mechanism selectively operable for producing different train control effects comprising a plurality of stick circuits, a vehicle carried control relay mechanism therefor, a vehicle carried inductor associated with said circuits for selectively energizing the same and a roadside mechanism for influencing the said inductor in the movement of the vehicle to selectively deenergize the circuits; and means for selectively determining the further condition of the circuits comprising reset circuits for said relay mechanism, an indication receiver means selectively operable for operating said reset circuits, a plurality of vehicle carried inductors for said indication receiver means and a plurality of roadside inductors cooperating therewith and associated with so as to be energized by said first mentioned vehicle carried inductor.
50. In an inductive train control system, vehicle carried mechanism selectively operable for producing different train control effects comprising a vehicle carried control relay mechanism, a vehicle carried inductor having primary and secondary coils associated with said relay mechanism and a roadside mechanism for influencing the said inductor in the movement of the vehicle to produce a controlling operation in said relay mechanism; and means for selectively determining the further operation of the relay mechanism comprising reset circuits for said relay mechanism, an indication receiver means selectively operable for operating said reset circuits, a plurality of vehicle carried impulse receiving inductors for said indication receiver means, a plurality of impulse transmitting roadside inductors cooperating therewith and an impulse receiving roadside inductor associated with so as to be energized by the primary coil of said first mentioned vehicle carried inductor.
51. In an inductive train control system, vehicle carried mechanism selectively operable for producing different train control effects comprising a vehicle carried control relay mechanism, a vehicle carried inductor associated with said relay mechanism and a roadside mechanism for influencing the said inductor in the movement of the vehicle to

produce a controlling operation in said relay mechanism; and means for selectively determining the further operation of the relay mechanism comprising reset circuits for said relay mechanism, an indication receiver means selectively operable for operating said reset circuits, a plurality of vehicle carried impulse receiving inductors for said indication receiver means, a plurality of impulse transmitting roadside inductors cooperating therewith, an impulse receiving roadside inductor associated with so as to be energized by said first mentioned vehicle carried inductor and changeable circuit connections between the roadside inductors.

52. In combination, electromagnetic vehicle carried mechanism, means for controlling the operation of the same including vehicle carried energizing and energy receiving inductors and roadside mechanism for influencing the inductors to produce a controlling operation of said vehicle carried mechanism in the movement of the vehicle over a roadway, and electro-manually controlled means for determining the further operation of the electromagnetic vehicle carried mechanism, said electro-manually controlled means being capable of being set only when the speed of the vehicle is reduced to a predetermined rate.

53. In combination, electromagnetic vehicle carried mechanism, means for controlling the operation of the same including vehicle carried energizing and energy receiving inductors and roadside mechanism for influencing the inductors to produce a controlling operation of said vehicle carried mechanism in the movement of the vehicle over a roadway, and electro-manually controlled means for restricting the operation of the electromagnetic vehicle carried mechanism, said electro-manually controlled means being capable of being set only after the speed of the vehicle is reduced to a predetermined rate.

54. In combination, vehicle carried mechanism, means for controlling the operation of the same including a vehicle carried energizing inductor and roadside mechanism for influencing the inductor to produce a controlling operation of said vehicle carried mechanism in the movement of the vehicle over a roadway, and manually operated electro-magnetic stick means for determining the further operation of the vehicle carried mechanism effective in continuing the vehicle under a predetermined rate of speed after the speed of the vehicle is reduced to said rate.

Signed at Niagara Falls, in the county of Niagara and State of New York, this 18th day of April, A. D. 1923.

ARCHIBALD G. SHAVER.
